THERMAL SWITCH WITH CYCLING DELAY

Edmond G. Franklin, Minneapolis, Minn., assignor to
General Mills, Inc., a corporation of Delaware

Application April 29, 1954, Serial No. 426,537

11 Claims. (Cl. 200—138)

This invention relates in general to thermal switches and pertains more particularly to a switch of this character having improved means for delaying the cycling of the contacts forming a part thereof.

One of the attendant disadvantages in prior art switches of this variety stems from the fact that they sometimes cycle too rapidly, for instance, where the thermally responsive means associated with the switch structure follows too closely the changes in temperature, endeavoring to control the current in a corresponding manner, the thermally responsive means may fluctuate in its operation to such an extent that the contacts will be made and broken very quickly reflecting these spasmodic temperature conditions. It is the relatively short time intervals between engagement and disengagement of the switch contacts that is extremely undesirable, particularly in certain types of appliances which must come up to specified standards such as those requirements stipulated by the National Electrical Manufacturers Association. On the other hand, the sensitivity may be of such a fine degree that there is what is commonly termed a chattering of the contacts, thereby precluding a clear cut engagement and disengagement of these elements. This results in unnecessary heating of the contacts, rendering them quite vulnerable to wear with an accompanying shorter life span than would normally be expected of them.

In an endeavor to combat the foregoing disadvantages certain steps have been taken to correct the situation. However, by and large these steps have resulted in either too costly a switch structure or switch structure that is unduly large and cumbersome. Accordingly, the instant invention has in view the correction of these problems in an inexpensive and facile manner.

One feature of the instant invention resides in the utilization of thermally expandable struts through which the current coursing through the contacts is directed. These struts upon expansion or contraction are instrumental in changing the relative displacement of one contact and its associated arm with the other contact and arm. Such action is in response to passage or interruption, respectively, of current through both the struts and contacts, the cross section of the struts being sufficiently small in relation to the current to generate enough heat to provide the expansion. In this connection, it is desideratum of the invention that the total amount of current passing through the contacts be directed through the struts. Stated differently, each of the struts contemplated in the practising of the present invention is in series with each other and the cooperable contacts of the switch.

Another object of the invention resides in the provision of a thermal switch having the foregoing thermally responsive strut elements which are arranged so as to amplify the expansion and contraction of these struts. By so doing, the struts cause a corresponding but greater relative displacement of the contact juncture of the struts in a direction perpendicular to the contact arm.

2

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawings:

Figure 1 is an elevational view, mainly in section, showing one form of the invention;

Figure 2 is a fragmentary view corresponding to Figure 1 showing a different operational position of the switch parts;

Figure 3 is another view similar to Figures 1 and 2, but showing a still different positioning of the switch parts;

Figure 4 is a graph showing a typical operation of a prior art switch without the improvement incorporated therewith that is envisaged by the present invention;

Figure 5 is a graph depicting a typical operation of the switch structure forming the subject matter of this invention;

Figure 6 is an elevational view of one of the contact arms before being bent into the configuration it assumes in Figure 1;

Figure 7 is a detail plan view corresponding to Figure 6;

Figure 8 is an elevational view similar to Figure 1, but showing a modified version of the switch construction and

Figure 9 is a plan view similar to Figure 7 showing a differently configured element playing an important role in the embodiment of Figure 8.

Referring in detail to the drawings, the thermal switch exemplified in Figures 1, 2, 3, 6 and 7 is designated in its entirety by the reference letter A. The switch A comprises a tubular post 10 having a shoulder or flange 12 at its lower end and a riveted upper end 14. Intermediate its ends 12 and 14 is disposed a plurality of operating members employed in a stacked arrangement to form the switch A. First it will be observed that a bimetallic element 16 carrying an upstanding insulating stud 18 at its free end encircles at its other end the tubular post 10. A pair of contact arms 20 and 22 also are supported in a cantilever manner by reason of the tubular post 10. Subjacent the riveted end 14 is a relatively rigid bracket member 24. Between these various members 16, 20, 22 and 24 is interposed a plurality of insulating spacers 26 suggestively of ceramic material.

Describing the contact arm 20 in greater detail it is to be discerned that this arm includes a resilient horizontal element bearing the numeral 28 and carried by this resilient element is a contact 30. At the free end of the element 28 and integral therewith is a first inclined strut 32 and extending toward the tubular post 10 is a second or companion strut 34. While these struts may be connected directly with each other in an integral fashion at their neighboring ends, nonetheless it may at times be desirable to utilize a rivet or bearing member 36 to resist wear in this region. With this in mind provision is made for supporting the rivet 36 by forming what can be termed an annular nexus 38 having an aperture 40 extending therethrough, the aperture 40 serving to accommodate the shank of the rivet 36.

Proceeding further with the detailed description of the contact arm 20, the strut 34 merges into a terminal strip 42, this strip having a U-shaped bend intermediate its ends at 44. The U-shaped portion renders the strip 42 quite flexible, so as not to impose any unwanted restriction on the movement of the contact arm 20. The end thereof lying opposite the strut 34 is anchored into place by means of the tubular post 10 and its associated elements. Since it is intended that the terminal portion 42

serve as the conductor for introducing current to the struts 32 and 34, a suitable layer of insulation 46 such as mica, is sandwiched between the terminal portion merging into the strut 34 and the underside of the resilient element 28. In order to anchor the upper end of the strut 34 with respect to the resilient element 28 a pair of insulating grommet halves 48 is utilized. These grommet halves or sections are disposed in suitable apertures 47 and 49 contained in the resilient element 28 and the terminal portion 42. A rivet 50 extends vertically through these grommet halves and in this way the above alluded to anchoring is achieved.

The second contact arm 22 is arranged in a vertically spaced relationship with the contact arm 20. This contact arm carries on its under surface a contact 52 which is cooperable with the first mentioned contact 30. Integral with the contact arm 22 is a terminal portion 54, this terminal portion being merely a direct continuation of the resilient arm 22. For adjusting the switch A for a preferred operation temperature, the bracket 24 has mounted thereon an adjusting shaft 56 having a threaded portion 58 which is received in a complementary aperture at the distal end of the bracket 24. At the lower end of the shaft 56 there is disposed an insulating stud element 60 which bears against the rivet 36 in the exemplified embodiment. However, it will be understood, as earlier herein before pointed out, that the rivet 36 may be dispensed with if desired. At the upper end of the shaft 56 is a knob 62 by which the shaft may be rotated to make the appropriate adjustment to the temperature at which the contacts 30 and 52 will separate or disengage. A stop element 64 serves as the agency by which the rotation of the shaft 56 is limited. Thus it will be appreciated that by inherently biasing the contact arm 20 in an upward direction, the insulating stud 60 opposes such an upward bias and by either raising or lowering the stud (by rotation of the knob 62) the upward bias is moderated or altered.

To permit the stud 60 to abut against the rivet 36 it will be noted that the resilient element 28 contains an aperture 66 therein, and the contact arm 22 contains a similar aperture 68, the stud 60 extending downwardly through both of these apertures. Also it will be recognized that the apertures are large enough to provide adequate clearance so that there is no interference with the movement of the contact arms 20 and 22. Further apertures 67 and 69 permit the encirclement of the element 28 and the terminal portion 42 about the tubular post 10.

Inasmuch as it is contemplated that the switch structure A be utilized in association with an electric heating appliance, the drawings additionally show a member 70 which may be the soleplate of an electric iron. Embedded in the soleplate 70 is a conventional encased heating unit 72, the opposite ends of which emerge upwardly and are designated by the numerals 74 and 76. The end 74 is connected to a conductor 78 leading to one side of a source of power L; the other end 76 is connected by a conductor 80 to the terminal portion 42, and the terminal portion 54 is in turn connected to the other side of the source L by reason of a conductor 82. Thus it can be seen that when the contacts 30 and 52 are engaged a conductive path is completed via the conductor 78, the heating element 72, the conductor 80, the terminal portion 42, the struts 34 and 32, a portion of the resilient element 28, the contacts 30 and 52 and the conductor 82 via the contact arm 22.

Having in mind the construction and arrangement of the principal elements hereinbefore described, it is believed that a complete understanding of my invention may now be had from a description of its operation. Assuming then that the contacts 30 and 52 have just been brought together, current will flow over the path mentioned in the preceding paragraph. By virtue of the particular cross section of the struts 32 and 34, how-

ever, the flow of current is instrumental in causing these struts to expand longitudinally, and due to the fact that their opposite ends are anchored with respect to the resilient element 28, the joined ends, that is the nexus 38 containing the rivet 36, will move downwardly with respect to the element 28. Actually though, since the element 28 is inherently biased upwardly, the longitudinal expansion of the struts 32 and 34 is responsible for permitting the contact 30 to bear with greater pressure against the contact 52 than it otherwise would at the first instance of engagement. Of course, once the current has begun to pass through the struts 32 and 34 it is only a moment before these struts expand sufficiently to increase the pressural contact of the contact 30 against the contact 52.

Continuing with the operational sequence of the thermal switch A, the contacts 30 and 52 having met causes current to flow through the heating element 72 at the same time that the current courses through the struts 32 and 34. The heating element 72 in turn heats the soleplate 70, and as the temperature of the soleplate is gradually raised, more and more heat will be radiated and/or conducted to the bimetallic strip 16. The heat received by the bimetallic 16 causes the strip to warp upwardly and the stud 18 abuts the underside of the contact arm 22 as pictured in Figure 2. It is the upward force applied to the contact arm 22 that causes separation of the contacts 30 and 52, this immediate separation being shown by the solid line position of the contact arms 20 and 22. As explained above, the cross sectional area of the struts 32 and 34 is such that these struts heat very quickly due to the passage of current therethrough. The converse is likewise true upon the cessation of current, for once the current has been interrupted then the struts cool and contract. The contracted position of the struts has been shown in dotted outline in Figure 2. Such a contraction of course, draws the resilient element 28 downwardly and the separation of the contacts 30 and 52 is immediately increased when the current flowing through them has been interrupted. This is so, since the stud 60 is in an abutting relationship with the rivet 36, and the contraction of the struts must draw the resilient element 28 downwardly, thus increasing the contact spacing as mentioned immediately above.

The solid line position of the switch parts depicted in Figure 3 is the same as the dotted line position thereof pictured in Figure 2. It is upon reaching the solid line position of Figure 3 that the contacts 30 and 52 are once again brought into engagement with each other and such engagement again causes current to course through the struts 32 and 34, thereby to heat and expand them. The expanded position of the struts is represented by the dotted outline shown in Figure 3 which is identical with the switch position pictured in Figure 1. Thus from the foregoing description it will be seen that a complete operational sequence has been described for the position shown in Figure 1 started with the contacts just after they had come together and the struts 32 and 34 had accordingly been heated and expanded.

While the above given operational description is thought to be entirely obvious and straightforward, nonetheless reference may now be had, if desired, to Figure 4. Here the curve labeled 84 illustrates the temperature of the soleplate 70 or other controlled device 70 plotted against time and it will be apparent that these cycles occur relatively rapidly with the peaks 86 and the valleys 88 being quite irregular. In such a situation the ordinary switch structure producing the graph of Figure 4 would not be equipped with the readily expandable struts 32 and 34 as in the exemplified embodiment. In contradistinction, the curve of Figure 5 is symbolic of the operation of the device just described in conjunction with Figures 1 to 3 for here the cycling delay mechanism operates to produce a wider spacing of the cycles in the curve 90 while at the same time the peaks 92 and depressions or valleys 94 are far more uniform.

Turning now to a discussion of Figures 8 and 9, attention is drawn to the fact that in large measure the parts constituting the switch B here presented are comparable or equivalent to those described in detail with respect to Figures 1 to 3. The primary difference in the modified version resides in the formation of the contact arm corresponding in function to the contact arm 20 of the earlier described embodiment, therefore, the modified contact arm has been given the reference numeral 100 and includes a resilient element or portion 102 which is relatively short. This element 102 has integrally connected thereto a strut 104 and a companion strut 106, these two struts as in the other embodiment being arranged at an obtuse angle with respect to each other. The strut 106 merges into a contact support 108 carrying a contact 110 which corresponds in function to the contact 30.

Bridging the opposite ends of the struts 104 and 106 is a rigid member 112 which may be of ceramic material or metal having an oxidized or silicone varnish surface 114. The purpose of the coating or surface 114 is to provide high electrical resistance contact by the member 112 when such member is metallic so that current coursing through the resilient element 102 will be compelled to traverse the struts 104 and 106 to provide the requisite heating effect thereof. Of course, if the member 112 is composed of ceramic material then the ceramic itself is a satisfactory insulator and precludes the flow of current by way of this member. Since the member 112 serves to anchor the opposite ends of the struts 104 and 106 relative to each other, suitable rivets 116 and 118 may be inserted through the contact arm 100. To provide for such insertion, apertures 120 and 122 are formed in the contact arm. As with the earlier described struts 32 and 34, if desired, the juncture thereof may be of annular configuration containing a rivet such as the rivet 36.

Inasmuch as the operation of the switch B is identical with that of the switch A, it is not deemed necessary to describe the functioning again in detail. In this connection, however, it will be appreciated that when the contacts 110 and 52 are engaged current will flow through the switch via the resilient element 102, being directed through the struts 104 and 106 on its way to the contact 110. The current, as in the previous embodiment, is instrumental in causing the struts 104 and 106 to expand, since from Figure 9 it can be seen that these struts are of relatively limited cross section compared to the cross section of the remainder of the contact arm 100. Upon cessation of current flow the struts 104 and 106 will again contract just as is the situation with respect to the struts 32 and 34.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. A thermal switch comprising a pair of cooperable contacts for controlling an electric current, a first temperature sensitive device arranged to effect initial separation of said contacts in response to increasing temperature, a second temperature sensitive device which prior to said initial separation is expanded through heating by current controlled by said contacts but which cools and consequently contracts after such separation due to the cessation of said current, thereby causing the gap between said contacts to increase as it cools, and means directly engageable with said second temperature device provid-

ing relative adjustment of said contacts for separation at a preferred temperature of said first temperature device.

2. A thermal switch comprising a pair of cooperable contacts for controlling an electric current, first means including a pair of inclined struts of electrically conductive material and a member anchoring the opposite ends of said struts in a substantially fixed spaced relationship with each other, one of said contacts being electrically connected to one of said struts, second means carrying the other of said contacts, manually adjustable means engageable with said struts adjacent their locus of juncture and thermally responsive means engageable with said second means, said struts having a cross-section limited with respect to the current controlled by the contacts for causing substantial expansion and contraction of the struts by heating and cooling in response to the changes in current carried by the struts on engagement and disengagement of the contacts.

3. A thermal switch in accordance with claim 2 in which said member has an oxidized surface.

4. A thermal switch comprising a pair of cooperable contacts for controlling an electric current, first means including a pair of inclined struts of electrically conductive material and a member anchoring the opposite ends of said struts in a substantially fixed, spaced relationship with each other, said member carrying one of said contacts, second means carrying the other of said contacts, manually adjustable means engageable with said struts adjacent their locus of juncture and thermally responsive means engageable with said second means, said struts having a cross-section limited with respect to the current controlled by the contacts for causing substantial expansion and contraction of the struts by heating and cooling in response to the changes in current carried by the struts on engagement and disengagement of the contacts.

5. A thermal switch comprising a first switch arm including a horizontal element supported at one end and a pair of inclined metallic struts connected together at one end, the other end of one of said struts being connected to the other end of said horizontal element and the other end of the other strut being insulatingly anchored to said horizontal member at a locus intermediate the ends of said horizontal element, a first contact carried by said horizontal element, a second switch arm, a second contact carried by said second arm cooperable with said first contact, manually adjustable means engageable with the connected ends of said struts, and thermally responsive means engageable with said second contact arm for moving said contacts relative to each other, said struts having a cross-section limited with respect to the current controlled by the contacts for causing substantial expansion and contraction of the struts by heating and cooling in response to the changes in current carried by the struts on engagement and disengagement of the contacts.

6. A thermal switch comprising a first switch arm including an elongated resilient element supported at one end, a first metallic strut integral with the other end inclining away from said element, a second metallic strut joined to the first strut and inclining toward said resilient element, terminal means connected to said second strut having a flexible portion, insulating means between said terminal means and said resilient element disposed intermediate said flexible portion and said second strut, means extending through said terminal means, said insulating means and said resilient element for anchoring the neighboring end of said second strut relative to the resilient element, a first contact carried by said resilient element, a second switch arm, a second contact carried by said second arm cooperable with said first contact, manually adjustable means engageable with the connected ends of said strut, and thermally responsive means engageable with said second switch arm for moving said contacts relative to each other, said struts having a cross-section

limited with respect to the current controlled by the contacts for causing substantial expansion and contraction of the struts by heating and cooling in response to the changes in current carried by the struts on engagement and disengagement of the contacts.

7. A thermal switch in accordance with claim 6 in which said terminal means is an integral continuation of said second strut and said flexible portion constitutes a U-shaped bend disposed substantially perpendicularly to the axis of said resilient element.

8. A thermal switch comprising a first switch arm including an elongated resilient element supported at one end, a first metallic strut integral with the other end inclining away from said element, a second metallic strut joined to the first strut at an obtuse angle at one end and having its other end remote from said element, a member of relatively high electrical resistance extending between the opposite ends of said struts, a first contact carried by said first switch arm adjacent said remote end of said second strut in an electrically conductive relation with said struts, a second switch arm, a second contact carried by said second arm cooperable with said first contact, manually adjustable means engageable with the connected ends of said strut, and thermally responsive means engageable with said second switch arm for mov- 25

ing said contacts relative to each other, said struts having a cross-section limited with respect to the current controlled by the contacts for causing substantial expansion and contraction of the struts by heating and cooling in response to the changes in current carried by the struts on engagement and disengagement of the contacts.

9. A thermal switch in accordance with claim 8 in which said member is a strip of metal having an oxidized surface.

10. A thermal switch in accordance with claim 8 in which said member is a strip of metal having a silicone varnish surface.

11. A thermal switch in accordance with claim 8 in which said member is a strip of ceramic material.
